UNITED STATES PATENT OFFICE.

GEORGE C. POWELL, OF CHICAGO, ILLINOIS, ASSIGNOR, BY DIRECT AND MESNE ASSIGNMENTS, TO EDWARDS & POWELL CO., OF CHICAGO, ILLINOIS, A CORPORATION OF ILLINOIS.

LEVEL.

1,286,767.

Specification of Letters Patent.

Patented Dec. 3, 1918.

Application filed January 22, 1917. Serial No. 143,695.

To all whom it may concern:

Be it known that I, GEORGE C. POWELL, a citizen of the United States, and a resident of Chicago, county of Cook, and State of Illinois, have invented a certain new, useful, and Improved Level, of which the following is a specification:

My invention relates to improvements in levels, the object being to provide a level of the kind commonly called mason's level, in which the spirit glasses or vials shall be so mounted as to be practically permanent in position; in which a minimum amount of stock shall be removed for the placement of the vials; which levels shall be capable of being manufactured at a minimum cost and which shall be stronger and more durable than the levels ordinarily used.

A further object of my invention is to eliminate, as far as possible, all possibility of deterioration and assure the permanency of the accurate adjustment of the vials or glass tubes.

My invention resides mainly in the manner of mounting the glass spirit tubes in the stock of the level which render possible the attainment of the above mentioned and other objects and it also consists in the several arrangements and combinations of parts and in the features of constructing as hereinafter described and particularly pointed out in the appended claims.

My invention will be more readily understood by reference to the accompanying drawings forming a part of this specification and wherein I have illustrated a preferred embodiment thereof.

In said drawings:

Fig. 1, is a fragmentary elevation of a mason's level made in accordance with my invention.

Fig. 2, is a vertical section on the line 2—2 of Fig. 1;

Fig. 3, is a fragmentary longitudinal section of the level on the line 3—3 of Fig. 2; and

Fig. 4, is a fragmentary section similar to Fig. 3, illustrating the manner of inserting the tubular supports.

My invention relates particularly to the manner of mounting spirit glasses in levels and consists primarily in first mounting metallic tubular supports 10 in the body of

the stock 11. The stock 11 has ordinarily sight openings 12, one adjacent each end thereof, for level glasses 13 and a central sight opening 14 for level glasses 15.

My invention has to do particularly with the mounting of the glasses 15 in the sight opening 14. These spirit glasses or vials 15 are arranged longitudinally in reference to the body of the stock and are substantially parallel with the side edges thereof. I prepare the opening 14 with parallel side walls 16 and semi-circular ends 17 as best shown in Fig. 3. The opening 16 is wide enough to permit the mounting of two of the tubes 15 parallel with each other. As I arrange the spirit levels the tubular supports are substantially in alinement with the grain of the wood of the level stock 11 and I insert these tubular supports 10 in the stock 11 by forcing them endwise into the body of the stock. In the figures of the drawings these tubular supports are shown in their final inserted positions and the fact that the tubes are forced into the body of the stock causes the wood of the stock to forcibly and wedgingly engage the surface of the tubes both inside and outside thereof.

In the operation of pressing or forcing the tubes into the stock no material of the stock is removed but the adjacent portions thereof are obviously compressed and hence the wedging engagement between tubes and the body of the stock mentioned is produced. For the purpose of clearly illustrating the manner of inserting the tubes I have shown a head 18, in Fig. 4, provided with socket openings 19 adapted to receive two of the tubes 10 and hold them in alinement and by means of which pressure can be applied to the tubes to force them into the stock, as shown. This head 18 is guided by the side walls 16 of the opening 14 and by means of the head the two tubes at one end of the openings 14 are first inserted then the head 18 is reversed and the two tubes at the opposite end of the opening 14 are similarly forced into position.

Each of the tubular supports has its free end 20 cut off at an angle of about 45 degrees, the shorter side being arranged adjacent to the middle of the opening 14, as shown in the drawings, and consequently the maximum distance between the oppositely

disposed tubular supports and the maximum exposure of the spirit glass is adjacent to the center line of the level.

The tubular supports having been inserted 5 as described I proceed to mount the spirit glass 15 therein. In preparation for this I have selected tubular supports which are slightly larger in internal diameter than the external diameter of the spirit glass to be mounted therein leaving a small space between the glass and the tubular supports 10 for the insertion of suitable cement. Before mounting the spirit glass in the opposite tubular supports I fill both of the tubular supports with suitable hardening cement and 15 thereafter I force one end of the spirit glass into one of the tubular supports a sufficient distance to permit the opposite end of the spirit glass to pass into the opposite tubular support and when the spirit glass has been 20 brought into alinement with the supports I move the spirit glass endwise to center it between the two supports. Then I force cement into the tubular supports to completely fill all voids. It is to be noted that 25 but a small quantity of the cement is necessary as the tubular supports substantially fit the spirit glasses, but a small space being left for cement between the two. Having 30 mounted one of the spirit glasses as described I proceed to mount the opposite glass in the same manner.

The usual manner of mounting the longitudinal spirit glass in levels is to provide 35 enlarged dove tailed sockets in the body of the level to receive a relatively large body of cement in which the ends of the spirit glass are embedded. The detrimental feature of this manner of mounting spirit glasses is 40 that it is practically impossible to make sure that all of the voids in these large dove tail openings are filled solid with cement, and even if they are filled substantially full of cement the body of the cement is necessarily 45 so large that it is liable to be fractured when the level is accidentally jarred by being struck or dropped. By my improved means of mounting spirit glasses I avoid the use of any large amount or body of cement and the tubular supports which I use are permanently held in the level stock and are not 50 subject to being displaced by any shock or jar.

As a final means of adjustment of the 55 spirit glasses, they having been placed in position, the level is placed upon a horizontal surface and then the spirit glass is pressed down at one end or the other to cause the bubble 21 to assume its proper position between the gage marks 22, at which 60 time the final insertion of the cement around the ends of the spirit glass in the tubular supports is accomplished by means of a suitable spatula.

65 The spirit glasses are protected by glass

plates 23 which are inserted into the body of the level at each side of the two spirit glasses, as shown in Fig. 3, and for this purpose I counterbore the opening 14 providing shoulders 24 upon which the glasses 23 are 70 supported. The glasses 23 are held in position by suitable fasteners 25 and putty 26.

Before mounting the tubular supports in the opening 14 I preferably paint the inside surface of the opening 14 with white paint, 75 so that, in use, the bubbles will be most distinctly shown.

By means of my invention I have eliminated the necessity of producing the sockets in the stock of the level at the ends of the 80 opening 14, which sockets it has always been difficult to make of suitable minimum size on account of the necessity of producing the sockets by means of a boring tool which had to be arranged at an angle longitudinally to the stock of the level in order to 85 produce the sockets in proper position.

As many modifications of my invention will readily suggest themselves to one skilled in the art I do not limit or confine 90 my invention to the specific structures herein shown and described.

I claim:

1. A wooden level stock provided with an opening adjacent to the middle of its length 95 extending from face to face and having end walls, aligned tubular vial supports parallel with the longitudinal edges of the stock and extending into said opening from the end walls thereof, the opposite ends of the tubes 100 projecting into said end walls and rigidly held thereby, the outer surfaces of said tube contacting firmly with the wood of the stock, and a spirit vial or tube extending within both said tubes and rigidly held 105 therein by suitable cement.

2. In a level having a wooden stock, a tubular vial support held in said stock in a socket having a bottom integral with the 110 stock.

3. In a level having a wooden stock, a tubular vial support held rigidly mounted thereon in a socket arranged parallel with the longitudinal side edges of the stock, the socket having a bottom integral with the 115 stock.

4. In a level having a wooden stock, a tubular vial support rigidly held in the stock by having one end thereof extending 120 into the body of the stock and contacting therewith, the wall at the inner end of the support being integral with the wooden body of the stock.

5. In a level having a wooden stock, a tubular vial support held rigidly in the 125 stock by having one end thereof extending into the body of the stock and contacting therewith both outside and inside of the tube.

6. In a level having a wooden stock, a 130

tubular vial support rigidly held therein with one end projecting into an opening provided in the stock by having the other end inserted into the body of the stock from 5 said opening, the material of the stock contacting with inserted end being integral with the remainder thereof.

7. In a level having a wooden stock, a tubular vial support driven or pressed into 10 the body of the stock and contacting firmly therewith both within and without the tube.

8. In a level having a wooden stock, a tubular vial support held firmly thereby in 15 a socket formed by driving the tube endwise into the body of the stock through the integral wall of an opening therein.

9. In a level having a wooden stock, a tubular vial support mounted in the wood of the stock by being pressed endwise into 20 same for about one half its length.

10. In a level having a wooden stock provided with an opening, opposed alined tubu-

lar supports pressed endwise into the body of the stock through the integral walls of 25 said opening and held thereby, in combination with a glass vial held within the said alined tubes, the vial being slightly smaller in diameter than the inner diameter of the tubes and rigidly held therein by cement.

11. In a level having a wooden stock, provided with a sight opening, opposed tubular vial supports pressed endwise into the body of the stock through the integral wall of 30 said sight opening and rigidly held thereby, the opposed free ends of the tubes being oppositely inclined for receiving and exposing 35 a glass vial.

In testimony whereof, I have hereunto set my hand this 29th day of December, 1916, in the presence of one subscribing witness. 40

GEORGE C. POWELL.
